Des. 1712

Henry G. Thompson, of New York, N.Y.
Assignor to the
Hartford Carpet Company.
Letter Patent No. 1712, Dated Jan. 27, 1863.

The schedule, referred to in these Letters Patent and making part of the same.

To all whom it may concern:

Be it known that I, H. G. Thompson, of the City, County and State of New York, have invented or produced a new and original Design for a Pattern to be imprinted upon 2-ply, Ingrain and other Carpets, in colors similar to those painted on the drawings accompanying this specification, or in other colors substituted in the place of those painted on the drawings (hereinbelow), and I do hereby declare that the drawings accompanying this specification, do give and convey to any one skilled in the art of Carpet weaving a more defined and thorough description of the nature of my invention than it is in the power of language otherwise to convey, and is sufficient to enable any one skilled in the art of Carpet weaving to use my invention.

Des. 1712

What I claim as my invention and desire to secure by Letters Patent, is the configuration of the Design hereunto annexed, when made by being in-wrought into 2-ply, Ingrain or other carpeting, in the form similar to the drawings accompanying this specification.
